DESIGN FOR A BOTTLE

Clyde W. Ahrens, New York, N. Y., assignor to Mission Dry Corporation, New York, N. Y., a corporation of Delaware

Application May 18, 1934, Serial No. 51,829

Term of patent 7 years

To all whom it may concern:

Be it known that I, Clyde W. Ahrens, a citizen of the United States, residing at New York, in the county of New York and State of New York, have invented a new, original, and ornamental Design for a Bottle, of which the following is a specification, reference being had to the accompanying drawing, forming part thereof.

I claim:

The ornamental design for a bottle, as shown and described.

In testimony whereof I affix my signature.

CLYDE W. AHRENS.
